UNITED STATES PATENT OFFICE.

FRANK TWYMAN, OF LONDON, ENGLAND.

DESIGN FOR A THERMOPILE.

44,225.

Specification for Design.

Patented June 17, 1913.

Application filed April 10, 1913. Serial No. 760,322. Term of patent 7 years.

To all whom it may concern:

Be it known that I, FRANK TWYMAN, a subject of the King of Great Britain and Ireland, and residing at London, England, have invented a new, original, and ornamental Design for Thermopiles, of which the following is a specification, reference being had to the accompanying drawing, forming part thereof.

The figure is a perspective view of a thermopile, showing my new design.

I claim:

The ornamental design for a thermopile, as shown.

F. TWYMAN.
